COMBINED SIGNAL LIGHT AND WATER SKI TOW HITCH

Andrew George Griparis, 1000 Westminster Road,
Joliet, Ill.

Filed Aug. 18, 1960, Ser. No. 61,818

Term of patent 14 years

(Cl. D71—1)

The figure is a perspective view of a combined signal light and water ski tow hitch showing my new design.

I claim:

The ornamental design for a combined signal light and water ski tow hitch, as shown.
